CLAIM

I claim the ornamental design for a shoe sole, as shown and described.

DESCRIPTION

FIG. 1 is a Perspective view of a shoe sole showing my new design;

FIG. 2 is a Front view of the shoe sole as shown in FIG. 1; FIG. 3 is a Back view of the shoe sole as shown in FIG. 1; FIG. 4 is a Right-side view of the shoe sole as shown in FIG. 1;

FIG. 5 is a Left-side view of the shoe sole as shown in FIG. 1;

FIG. 6 is a Top of the shoe sole as shown in FIG. 1; and, FIG. 7 is Bottom view of the shoe sole as shown in FIG. 1. The broken lines show environmental structure and portions of the shoe sole that form no part of the claimed design.
